UNITED STATES PATENT OFFICE.

JOHN EDWARD ANGER, OF PRESTON, ENGLAND.

SLACK-ADJUSTER FOR BRAKES.

1,178,375.

Specification of Letters Patent.

Patented Apr. 4, 1916.

Application filed February 2, 1915. Serial No. 5,722.

To all whom it may concern:

Be it known that I, JOHN EDWARD ANGER, a citizen of the United States of America, residing at Preston, in the county of Lancaster, in the Kingdom of England, have invented certain new and useful Improvements in Slack-Adjusters for Brakes, of which the following is a specification.

This invention relates to slack adjusters 10 for railway and tramway brakes, and more particularly to that type in which compensation for wear is taken up by means of a ratchet driven screw mechanism.

The present invention consists in certain 15 improvements in brake adjusters of the type referred to also in the application of such adjusters to any one of the several positions in which it is desired to locate the same, having regard to the class of truck or bogie to 20 which the brake is applied, and as to whether the brake shoes are outside hung at ends of the truck, or are inside hung, that is between the wheels.

My invention further consists in various 25 combinations and arrangements of parts which will now be described, and the novel features of which, will be pointed out in the appended claims.

In the drawings Figure 1 is a face view 30 of brake slack adjuster; Fig. 2 a vertical section on line *a b* of Fig. 1, and Fig. 3 an edge view; Fig. 4 is a side view showing the brake slack adjuster applied to an equal wheel bogie truck wherein the brake applies 35 its pressure from between the wheels, and Fig. 5 is an end view of so much of the said truck as is necessary to show the adjuster.

Referring to the drawings, it will be seen 40 that the slack-adjuster comprises a rod 1 provided with a left-hand thread for engaging a corresponding thread in a non-rotatable buckle 2, while the other end of the said rod is provided with a right-hand thread for engaging a corresponding thread in a non- 45 rotatable buckle 3. At mid-length the rod 1 is not threaded, and on this unthreaded portion is mounted a sleeve 4 having ratchet teeth 5 on its periphery. This sleeve is locked to the rod by the pins 6, so that the 50 rod will be turned by the ratchet teeth 5 which work solidly with the sleeve, and by this means the rod is adjusted as regards its length, the end buckles 2, 3, being held against rotation. Journaled freely on the 55 sleeve so as to oscillate thereon is a housing

7, 8. This housing is in the form of a box 7 inclosing the ratchet wheel 5, and freely mounted on the sleeve so as to oscillate thereon, and a cover or lid 8 also freely mounted on the sleeve on the opposite side 60 of the ratchet wheel to the box 7, this being secured to the box by bolts 9, whose threads are screwed into holes in the cover, as well as being secured by nuts, so as to form a nut-lock. The abutting faces 10 of the box 65 and cover are machined so as to make a dust proof joint, and the housing 7, 8 has center bosses 7^x and 8^x so as to provide a good wide bearing on the sleeve. Grooves 11 are cut in those parts of the outer periphery of the 70 sleeve on which the housing 7, 8 is journaled, which grooves receive a suitable lubricating material, which not only lubricates the said journal bearings, but closes the joint between the said housing and sleeve so as to render 75 the housing absolutely dust, dirt and water proof. The portion of the end of the sleeve 4 which projects beyond the housing is angular, so that it can be turned by a spanner or by hand. The inside of the housing is 80 provided at one part with an embayment 13, in which is pivotally mounted by means of trunnions a pawl 14, which is held in engagement with the ratchet wheel by means of a spring 15. The trunnions 16 of this 85 pawl which are tubular extend through holes in the housing 7, 8 said holes having extension bosses 17 so as to provide a good bearing surface for the trunnions. Through the trunnions passes a spindle 18, and integral with this spindle on the outside of the housing is the thumb lever 19 to disengage the pawl from the ratchet wheel when required. The spindle 18 has longitudinal feathers 20 integral with the spindle and thumb lever. These interlock with corresponding slots in the trunnions when the spindle is thrust longitudinally into them, so that the turning of the thumb lever will turn the pawl, the other end of the spindle 90 being secured by a washer and split pin.

On the outside of the housing is a pair of lugs 21 between which one end of a chain or the like 22 is secured by means of a link 23 and bolt 24, and also another pair of lugs 25 is provided, to which one end of the spring 26 is connected by the bolt 27, this spring being adapted to exert its pull in a contrary direction to that exerted by the chain, thus oscillating the housing back 105 110

when the temporary application of the brake is discontinued. One of these lugs in each pair is cast on the box member 7 of the housing and the other on the cover 8, and these latter are off-set so as to form shoulders 28 with which the box member 7 engages. The shoulders 28 are rectilinear (*i.e.* flattened) as shown in Fig. 1 and the corresponding parts 29 of the box member are 10 also rectilinear so that when the cover 8 and the box member 7 are brought together, these rectilinear portions interlock, and insure the lugs being in register. The bolts 24 and 27 have their threads screwed into 15 one of the lugs as well as being secured by nuts, so as to form a nut-lock. Figs. 4 and 5 show an arrangement for applying the adjuster to a brake which exerts its pressure from the inside, that is between the wheels, 20 the type of truck illustrated in these figures being the equal wheel bogie truck of a bogie truck car. Referring to these figures, the brake comprises two brake beams 30, 31, which extend across the vehicle adjacent to 25 the wheels and operate the brake shoes 32, the brake beams and brake shoes being suspended by links 33 from the bolster 34 of the truck. At about mid-length of the brake beam 30 is bolted the brake rod 35, which 30 has a pivoted connection with the live brake lever 36. The said brake lever 36 operates in a vertical plane, and its long arm is coupled to the pull rod for putting on the brake, such rod being operated by hand 35 power, or by compressed air, or by vacuum, or by any other suitable form of brake mechanism. At mid-length of the brake beam 31 is bolted a brake rod 37, which is pivotally connected with the dead brake lever 38. 40 The long arm of said brake lever abuts against the bolster 34, which serves as a stop, and assumes the strain which is imposed when the brake pressure is applied. To the short arms of the brake levers 36, 38, 45 are respectively coupled by pins 39, the buckles 2, 3 of the adjuster hereinbefore described, such adjuster together with its rod being located longitudinally of the bogie, that is at right angles to the wheel axles, 50 directly below the brake rods 35 and 37 at about mid-width of the truck or the like. The chain 22 which is secured to the outside of the housing of the adjuster is passed over a guide pulley 40, and has its other 55 end secured to the brake lever 36 by means of a shackle 41, which shackle is secured to the brake lever by a bolt 42 passing through the slot 43. Serrations 44 are provided on the brake lever 36 in which corresponding 60 serrations on the shackle 41 engage when the bolt 42 is screwed up. The spring 26 which is also connected at one end to the outside of the housing of the adjuster, is at its other end secured to an eye piece of an 65 adjustable bolt 45, said spring being in ten-

sion. The brake shoes are held normally clear of the wheels by plate springs, such springs being secured to the bolster 34 so as to depend therefrom and act on the brake beams 30, 31, also forcing the live brake lever 36 back to its normal position, when the temporary application of the brakes on the wheels is discontinued. In operation the brake lever 36 is pulled outward, and this causes the brake shoes of both brake beams 30, 31 to be applied to the wheels, and also pulls the chain 22 which oscillates the housing 7 in the direction of the arrow (Fig. 5). Should the lever 36 from the wear of the shoes travel farther than a given distance, this motion of the housing will cause the pawl 14 to travel more than the length of one tooth of the ratchet wheel. The pawl will then hold in that tooth and remain there until the brakes are released. 80 Upon releasing the brake, the plate springs will force the brake beams 30, 31 and brake lever 36 back, and the spring 26 will oscillate the housing back, which will cause the pawl to rotate the ratchet 5, whereby the threaded extremities of the rod 1 will be screwed out of the buckles 2, 3 a little. The distance between the buckles is consequently increased, and the brake levers 36, 38 are pushed farther apart, thus taking up superfluous slack. This operation is repeated as often as the travel of the brake lever 36 exceeds the normal. It will be seen that in this application of the invention, only one 85 adjuster is required, to take up the slack of four brake shoes. When new brake shoes are to be substituted, for those which have been worn out, the rod 1 between the 90 brake levers 36 and 38 is shortened, so that the brake beams will swing inward far enough to leave the necessary clearance for the new shoes. This is readily done by lifting the pawl out of engagement with the teeth of the ratchet wheel, by means of the 95 thumb lever 19, and then rotating the rod 1 in a reverse direction, by applying a spanner to the angular end of the sleeve 4. 100

I declare that what I claim is—

1. In a brake slack adjuster, the combination with a threaded brake rod, and a ratchet driven nut or sleeve engaging the same, of a closed housing journaled on the nut or sleeve for inclosing the ratchet wheel, center bosses on the housing for providing wide journal bearings, and grooves cut in those parts of the outer periphery of the sleeve or nut on which the housing is journaled, which grooves receive a lubricating material to close the joint between the said housing and sleeve or nut. 115

2. In a brake slack adjuster, the combination with a threaded brake rod, and a ratchet driven nut or sleeve engaging the same, of a closed housing journaled on the nut or sleeve for inclosing the ratchet wheel, lugs 120

on the exterior of the housing, a chain coupled to one pair of lugs to oscillate the housing in one direction, a take up spring coupled to the other pair of lugs to exert a pull 5 on the housing in the reverse direction, and a pawl for operating the ratchet.

3. In a brake slack adjuster, the combination with a threaded brake rod, and a ratchet driven nut or sleeve engaging the same, of a 10 closed housing journaled on the nut or sleeve for inclosing the ratchet wheel, lugs on the exterior of the housings, a curved link passing part way around the housing and coupled to the lugs, for the connection thereto 15 of a pull chain.

4. In a brake slack adjuster, the combination of a sleeve having ratchet teeth, a rod extending through the said sleeve and secured thereto, the said rod having oppositely 20 disposed threaded ends, interiorly threaded buckles for engaging the said threaded ends, brake levers to which the said buckles are coupled by pins, a housing journaled freely on the sleeve so as to inclose the ratchet teeth, 25 and a pawl inside the housing for operating the said ratchet teeth.

5. In a brake slack adjuster, the combination of a brake rod holding on at one end to one brake beam, a second brake rod holding on at one end to the other brake beam, and having pivotal connections at the other 30 end with the respective brake levers, a

ratchet driven rod having oppositely disposed threaded ends screwed into interiorly threaded buckles which are coupled to the 35 short arms of the respective brake levers, a housing inclosing the ratchet wheel, a pawl carried thereby for engaging the ratchet teeth, and a chain coupled at one end to the housing and at the other to the long arm 40 of the live brake lever.

6. In a brake slack adjuster, the combination of a brake rod holding on at one end to the brake beam, and having pivotal connections at the other with the brake lever, 45 a ratchet driven screw for adjusting the position of the brake beam relatively to the wheels, a housing inclosing the ratchet wheel, a pawl carried thereby for engaging the ratchet teeth, a chain coupled at one end 50 to the housing and at the other provided with a shackle, secured to the brake lever by a bolt passing through a slot in the brake lever, serrations on the brake lever at each side of the slot, and corresponding serrations on the shackle which engage together 55 when the bolt is screwed up.

In witness whereof, I have hereunto signed my name this 21 day of January 1915, in the presence of two subscribing witnesses. 60
